UNITED STATES PATENT OFFICE.

FRANK C. GIVENS, OF TUOLUMNE, CALIFORNIA.

SPRING.

1,134,839.

Specification of Letters Patent.

Patented Apr. 6, 1915.

Application filed November 3, 1914. Serial No. 870,092.

To all whom it may concern:

Be it known that I, FRANK C. GIVENS, a citizen of the United States, and a resident of Tuolumne, in the county of Tuolumne and State of California, have invented certain new and useful Improvements in Springs, of which the following is a specification.

My invention relates to springs, particularly to extensible springs having a contractile effect, and one of the main objects thereof is to provide such springs which allow extension up to a definite point but beyond which will result in breakage of the parts.

15 A further object is to provide such springs which will always return to initial position when relieved of tension.

20 A further object is to form the spring of two members in pivotal connection having two points of applied strain and being extensible along a line perpendicular to a line taken through the pivotal points; and further objects are to provide such springs which are simple in construction, which are 25 adapted for objects whose movement it is desired to limit, and which are very inexpensive.

30 My invention is fully described in the following specification, of which the accompanying drawings form a part, in which the separate parts are designated by the same reference characters in each of the views, and in which:—

35 Figure 1 is a side view of one form of the spring in operative connection with a pivoted lever; and Fig. 2 is a rear view of the spring alone.

40 In the drawings forming a part of this application I have shown one form of embodiment of my invention, comprising a member 3 coiled upon itself centrally at 4 and formed into arms 5 and 6, each of which is provided with an eye 7, and a member 8 centrally coiled upon itself at 9 and 45 formed into arms 10 and 11 having, each, an eye 12 engaged with the corresponding eye 7, and the tendency of the members is to draw the arms thereof into line, and thus, jointly, drawing the coils 4 and 9 into contact.

50 In Fig. 1 I have shown a fixed support 13

having an arm 14 secured thereto and to the outer end of which, at 15, is pivoted a lever 16 engaged with a ring 17 passed within the coil 9, whereas a similar ring 18 is secured to the fixed support and passed within the coil 4, the spring maintaining the lever in the position shown in full lines when no tension is applied thereto. When tension is so applied, the lever may move to the position indicated by dotted lines, at which time the arms of each member 3 and 8 are in line, the arm 5 with the arm 10, and the arm 6 with the arm 11, and no further extension of the spring is possible without 60 breakage or separation of the members thereof, and the lever movement is stopped. When the tension on the lever is relieved, the resiliency of the wire or other material of the spring members, at the coils thereof, 65 returns the spring members, and therefore the lever, to initial positions.

I may form my members of any suitable material, of any desired conformation, similar or dissimilar as to each member, and 70 may pass the material around as many turns as desired to form the coils, and various other changes in and modifications of the form shown and described may be made, as long as the spring is limited, because of its 75 construction, in the degree of extensibility.

Having fully described my invention, what I claim as new, and desire to secure by Letters Patent, is:—

1. A spring comprising two members in pivotal connection having arms thereon serving as means for preventing extension of said spring beyond a fixed point.
2. A spring comprising two members having, each, a coil therein forming arms on each side of said coil, said arms being in pivotal connection, and serving as limiting means to the extension of said spring.
3. A spring comprising two members having, each, a coil formed centrally therein, to form oppositely directed arms, each of said arms being formed into an eye, and corresponding eyes being engaged to lock the respective arms together, said arms serving as limiting means for the extension of said 100 spring.
4. A spring comprising two members hav-

ing, each, a coil centrally thereof, oppositely directed arms having, each, an eye formed at the end thereof and the corresponding eyes being in engagement, and a ring in each of said coils, the line of extension of said spring being on a line bisecting and perpendicular to a line drawn through the connections of opposite arms.

In testimony whereof I have signed my name to this specification in the presence of 10 two subscribing witnesses.

FRANK C. GIVENS.
